UNITED STATES PATENT OFFICE.

WILLIAM H. WINSLOW, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,339, dated July 13, 1897.

Application filed June 15, 1897. Serial No. 640,925. Term of patent 14 years.

To all whom it may concern:

Be it known that I, WILLIAM H. WINSLOW, a citizen of the United States, residing at Chicago, in the county of Cook and State of Illinois, have invented and produced a certain new and useful Design for Prism-Lights, of which the following is a description.

My invention relates to a design for prism-lights, and is illustrated in the accompanying drawing.

A is the border or frame; B, prisms projecting from the several prism-lights; C, the corners of the prism-lights shown as cut; D, the opaque rectangular pieces between the

prism-lights at the corners, and E the opaque strip between the prism-lights.

The essential features of my design are a prism-plate having a series of rectangular prism-lights with corners cut off and opaque strips between the lights and at the corners, as indicated.

I claim—

The design for a prism-light substantially as shown and described.

WILLIAM H. WINSLOW.
